ALBERT F. ALLEN, OF PROVIDENCE, RHODE ISLAND.

Letters Patent No. 77,437, dated May 5, 1868.

IMPROVEMENT IN THIMBLE-PULLER.

The Schedule referred to in these Letters Patent and making part of the same.

TO ALL WHOM IT MAY CONCERN:

Be it known that I, ALBERT F. ALLEN, of the city and county of Providence, and State of Rhode Island, have invented a new and improved "Thimble" Puller for removing the "thimbles" or "ferrules" from the tubes of steam-boilers; and I do hereby declare that the following is a full, clear, and exact description of the same, reference being had to the accompanying drawings, making part of this specification, in which—

Figure 1 is a longitudinal view of my machine, as used for removing the ordinary thimble or ferrule from boiler-tubes.

Figure 2 is a like view of the same, as used for removing screw-thimbles, which are screwed instead of being driven into the end of boiler-tubes.

Figures 3, 4, 5, 6, 7, 8, are details of the construction of my machine.

Similar letters indicate corresponding parts in all the said figures.

The thimble, (or ferrule, as it is sometimes called,) above referred to, is a ring of wrought iron (generally,) which is driven or screwed into the end of the boiler-tube, to keep it expanded in the flue-sheet and preserve the joint which is formed therewith around the end of the tube. In consequence of the moisture and gases which are generated within the boiler, the said thimbles become in a short time corroded to that extent that they become as immovably fixed in their place as though they were a part of the tube itself; so much so in fact that it has hitherto been found necessary to cut the thimble in two pieces in order to remove it, which, without exception, is attended with such injury to the end of the tube as to require resetting, and in most cases piercing out to provide for the removal of the injured portion at the end. By means of the machine which I have devised, and which is herein described, I am enabled to readily remove the thimble from the end of the tube, no matter to what extent it is corroded, without injury to the joint formed with the flue-sheet around it, much less to the end of the tube.

My invention, for this purpose, consists of a set of expandible catches or jaws, on a suitable mandrel or stock, that are capable of attaching themselves firmly to the thimble in the tube; a surrounding sleeve which serves as a fulcrum by resting against the contiguous portion of the tube or flue-sheet; and a screw-thread on the mandrel, with a screw-nut turning thereon, and bearing against the sleeve or fulcrum in such a manner, that, by the turning of the nut, the thimble attached to the catches or jaws is forcibly drawn, by the force thus exerted upon the screw, from within the end of the tube.

And my invention further consists in constructing the said catches or jaws with external serrated or scored surfaces, so as to be capable of attaching themselves by forcible expansion to the inner surface of a thimble, such as is described, and in combination therewith, suitable means for attaching a wrench or other turning-lever to the mandrel holding such jaws, for the purpose of unscrewing and removing such thimbles as are secured in the end of the tube by screwing.

In the said drawings, A, figs. 1 and 2, is the thimble, which is a stout non-collapsible ring of wrought metal, slightly tapering on the outside, which is either turned smooth or has a screw-thread cut upon it, according to the mode of its use.

E E E are the expandible catches or jaws, extending longitudinally from the hub or collar T of the mandrel H, each jaw being, for the sake of strength, formed as shown in figs. 7 and 8, with stout trunnions or arms b b, forming part of the same, upon which the jaw turns in the collar T. These trunnions are fitted into the two parts of the collar, as shown clearly in figs. 2, 3, and 4, the movable part T' of said collar, being secured in its place by means of the pin S, (fig. 2.) The mandrel H, (of which the collar T forms a part,) has a hole, I, longitudinally through the centre, (figs. 3 and 4,) for the reception of the stem d of the adjusting or expanding-wedge F, which forms a sort of triangular head thereto, and which fits nicely between the several catches, and by means of the thumb-screw nut h, fig. 2, at the end of the said stem, is made to press the said wedges outward, and effect their expansion so as to fasten to the thimble in the tube. A sleeve, M is fitted to slide easily on the said mandrel, and encloses the collar and a portion of the catches or jaws, the office of which is to afford a rest or support around the thimble, against which force may be exerted to withdraw the thimble from the tube.

The tubular portion of the mandrel is furnished with a screw-thread, on which a large hexagonal nut, P, turns, and has a bearing against the rear end of the said sleeve, by means of which, by turning the screen, the jaws or catches E, and the thimble to which they are attached, are drawn into the sleeve and out of the boiler-tube.

In case the thimble is screwed into the end of the boiler-tube so that it cannot be drawn out by the application of direct longitudinal pressure, as in the manner just described, the guide-jaws are made to attach themselves to the interior surface of the thimble, by the expansion alluded to, by making the exterior face or bearing α of said jaws with teeth, or otherwise roughened, to prevent slipping, and to indent and catch upon the said surface of the thimble, and the said mandrel H is squared at G, to receive a wrench by which it, with its jaws, may be turned to unscrew the thimble from the tube. The collar of the mandrel may also be formed to receive a wrench, or may be drilled to receive a lever or rod by which to turn the mandrel for the unscrewing of the thimble. In the use of the apparatus for removing screw-thimbles, the sleeve is unnecessary.

What I claim as my invention, is—

The combination of the expandible catches or jaws E E E, or their equivalent, the expanding-wedge F, the sleeve M, and the screw-mandrel H, and nut P, constructed substantially as described for the purpose set forth:

ALBERT F. ALLEN.
